CUTTINGS REMOVING MECHANISM

John A. Hayward, Claremont, N. H., assignor to
 Joy Manufacturing Company, a corporation of
 Pennsylvania

Application July 12, 1947, Serial No. 760,614

15 Claims. (Cl. 262—30)

1
 This invention relates to cuttings removing mechanism and more particularly to cuttings removing mechanism especially designed for use with a conventional room and pillar type coal cutting machine.

In conventional coal cutting machines, particularly those of the modern, high capacity, room and pillar type, the cuttings created by the cutter chain of the machine during the cutting operation rapidly accumulate and pile up at the rear end of the machine, and in order to prevent a substantial portion of the cuttings from being carried back into the kerf by the return run of the cutter chain, the cuttings must be rapidly removed from the vicinity of the cutter chain. Several known types of mechanisms have been used for mechanically removing the cuttings from the vicinity of the cutter chain of a coal cutting machine and for ejecting the cuttings from the machine; and the present invention contemplates improvements over such known mechanisms in that the cuttings are effectively removed from the vicinity of the cutter chain and forcibly ejected rearwardly from the machine while reducing to a minimum movement of the cuttings back toward the cutter chain. The cuttings removing mechanism of the present invention may be embodied in a coal cutting machine and driven by the machine motor, and embodies desirable features whereby ruggedness, compactness and efficiency are attained. Due to the particular arrangement and construction of the cuttings removing devices, not only are the cuttings effectively removed from the vicinity of the cutter chain and ejected from the machine but also the carrying back of the cuttings toward the cutter chain is greatly reduced.

It is an object of the present invention to provide an improved cuttings removing mechanism. Another object is to provide an improved cuttings removing mechanism especially designed for use with a room and pillar type coal cutting machine for mechanically removing the cuttings from the vicinity of the kerf cutter. A further object is to provide an improved mechanism for mechanically removing the cuttings from the vicinity of the cutter chain of a coal cutting machine and for positively ejecting the cuttings rearwardly out of the machine path and into the bottom of the pile of ejected cuttings. Yet another object is to provide an improved cuttings removing mechanism embodying a horizontally movable cuttings engaging and moving element and having improved supporting and driving means for said element whereby when the cuttings have

been moved outwardly and discharged, the cuttings engaging and moving element is moved into an inoperative position and maintained there during retraction thereof. A still further object is to provide an improved cuttings removing mechanism embodying oscillatory cuttings engaging and moving elements and improved driving mechanism for effecting oscillation of said elements. Still another object is to provide an improved cuttings removing mechanism embodying oscillatory paddles or bladelike scoops and improved driving means for oscillating the same together with means for moving the paddles or scoops into an inoperative position and maintaining them there during retraction thereof whereby movement of cuttings toward the cutter chain of the coal cutting machine is reduced to a minimum. Still another object is to provide an improved oscillatory paddle or bladelike scoop for pushing or scooping out the cuttings from the vicinity of the cutter chain, and improved means for actuating the paddle or scoop during operative movement thereof together with means for turning the paddle or scoop to an inoperative edgewise position during retraction thereof. A further object is to provide a pair of improved coating paddles or bladelike scoops mounted for movement in out of step relation in a novel manner and having improved supporting and driving means. A still further object is to provide a pair of coating paddles or bladelike scoops arranged and constructed in a novel manner. These and other objects and advantages of the invention will, however, hereinafter more fully appear.

35 In the accompanying drawings there is shown for purposes of illustration one form which the invention may assume in practice.

In these drawings:

40 Fig. 1 is a top plan view of a coal cutting machine having an illustrative form of the improved cuttings removing mechanism associated therewith.

45 Fig. 2 is a side elevational view of the coal cutting machine and cuttings removing mechanism shown in Fig. 1.

Fig. 3 is an enlarged fragmentary rear end elevational view of the coal cutting machine and cuttings removing mechanism shown in Figs. 1 and 2.

50 Fig. 4 is an enlarged cross-sectional view taken substantially on line 4—4 of Fig. 1.

Fig. 5 is a view in longitudinal vertical section taken substantially on line 5—5 of Fig. 1.

Fig. 6 is a horizontal sectional view taken substantially on line 6—6 of Fig. 3.

3

Fig. 7 is a detail vertical section, on an enlarged scale, taken on line 7—7 of Fig. 6.

Fig. 8 is a detail horizontal sectional view taken on the planes of line 8—8 of Fig. 4.

Fig. 9 is a developed vertical sectional view, on an enlarged scale, taken substantially on the curved line 9—9 of Fig. 1.

Fig. 10 is a developed detail view showing the cam surfaces for actuating the locking plungers.

Fig. 11 is a detail vertical sectional view taken on line 11—11 of Fig. 9.

Fig. 12 is a horizontal sectional view taken on line 12—12 of Fig. 4.

Figs. 13, 14 and 15 are sectional views taken on the plane of Fig. 6, respectively showing the moving parts of the cuttings removing mechanism in different positions.

In this illustrative embodiment of the invention, as shown in the drawings, the improved cuttings removing mechanism, generally designated 1, is associated with a coal cutting machine, generally designated 2, herein of the flexibly fed, room and pillar, floor cutter type. Evidently, the cuttings removing mechanism may be associated with coal cutting machines of other types.

The coal cutting machine disclosed herein may be similar to that disclosed in the J. F. Joy and L. E. Simmons Patent No. 2,131,178, patented September 27, 1938, and comprises a machine frame 3 slideable on its bottom 4 on the floor of a mine. Extending longitudinally throughout the length of the lower portion of the machine frame is a chamber 5 having arranged therein and secured to the machine frame a rearward portion of an elongated kerf cutter 6 comprising a horizontal plane cutter bar 7, the latter having guided for circulation about its margin an endless cutter chain 8. The machine may be fed and guided, both during maneuvering and the kerf cutting operation, by feeding and controlling drums 9 and 10, arranged on horizontal axes at opposite sides of the machine frame and having respectively wound therein feeding and controlling cables 11 and 12. Carried by the machine frame is a motor 13 having its power shaft operatively connected to the cutter chain, and the feeding and controlling drums for effecting drive thereof are fully described in the patent above referred to.

The feeding and controlling cables 11 and 12 may be extended from the drums 9 and 10 around appropriately located guide sheaves on the machine and may be led from opposite sides of the machine to suitable anchor jacks located at the ribs of the room of a mine. The cutter chain may then be connected in driven relation with the motor 13 to effect rapid circulation thereof about the margin of the cutter bar 7, and the drums 9 and 10 may be operatively connected to the motor to cause rotation thereof in a direction to wind in the cables to sump the cutter bar beneath the coal at the right hand rib and the cutter bar may thereafter be fed by the feed cable 11 transversely across the coal face, under the guidance of the controlling cable 12, to cut a horizontal kerf beneath the coal, and finally the cutter bar may be withdrawn by the feed cable from beneath the coal at the left hand rib to complete the cut. The feed drum 9 effects feed of the machine, and the controlling drum 10 serves to guide the machine with respect to the coal face during the kerf cutting operation in manners well known to those skilled in the art. During the kerf cutting operation, the cuttings created by the cutter chain are carried back from the kerf by the cutter chain through the

4

chamber 5 extending through the lower portion of the machine frame to discharge at the rear end of the machine. Since the mode of operation of a room and pillar coal cutting machine is well known and is fully described in the patent above referred to, further description thereof is herein unnecessary.

The improved cuttings removing mechanism 1 is herein suitably attached to the rear end of the coal cutting machine and is arranged in such a manner that it receives the cuttings discharged from the machine frame chamber 5 and removes the cuttings from the vicinity of the rear portion of the kerf cutter and ejects the cuttings rearwardly from the machine out of the machine path. The cuttings removing mechanism comprises a casing 15 secured to the machine frame and having a horizontal chamber 16 which forms a continuation of the chamber 5 within which the rearward portion of the kerf cutter is arranged, as shown in Fig. 5, and the cuttings are discharged from the chamber 5 into the casing-chamber 16. The casing-chamber is open at 17 at the rear side of the casing. Arranged in the casing-chamber 16 are coating cuttings removing devices 18 and 19, herein preferably identical in design and arranged to oscillate about parallel upright axes spaced equi-distantly from the longitudinal center of the casing near the opposite sides of the latter, and each including a paddle or bladelike scoop 20 mounted to oscillate horizontally about a vertical axis and to oscillate in a vertical direction about a horizontal axis which extends radially from the vertical axis. The paddles or bladelike scoops are mounted at opposite sides of the longitudinal center of the casing in the casing-chamber, and their ends swing in alternation across the longitudinal center of the casing chamber with the lower edge 21 of the paddles, when the latter are in upright effective position, running close to the bottom of the casing-chamber 16, as shown in Fig. 4. Each paddle or scoop has a horizontal shaft 22 journaled in spaced bearings 23, 23 supported within a cylindrical member 24, the latter in turn having a vertical shaft 25 (Fig. 4) journaled in spaced bearings 26, 26 respectively supported in bearing brackets 27 and 28, the latter formed integral with the lower portion of the casing 15, as shown in Fig. 4, and the upper bracket formed integral with a detachable top cover 29. Keyed to the vertical shafts 25 are spur gears 31 and 32, with which mesh gear segments 33 and 34 (Fig. 8) formed at the opposite sides of an oscillatory drive member or rocker 35 journaled to turn horizontally on a bearing 36 supported by a vertical stub shaft 37 integral with a horizontal plate 38. The plate 38 is arranged between the top cover 29 and the casing 15 and is rigidly secured to the latter and provides a top closure for the chamber 16. The gears 31 and 32 and the gear segment member 35 are arranged in a horizontal chamber 39 between the top cover 29 and the plate 38. The casing 15 has spaced horizontal projections 40, 40 providing curved sealing surfaces 41 which fit closely against the opposite sides of the exterior surfaces of the cylindrical members 24, as shown in Fig. 6, to prevent entry of dirt into the spaces 42 which may contain a lubricant. A spur gear 43 is secured to a vertical shaft 44 journaled within bearings 45 and 46, respectively supported within the top cover 29 and a detachable upper housing 47 secured to the top cover. The gear 43 has an integral crank pin 48 received in an elongated slot 49 in the oscillatory

gear segment member 35 for oscillating the latter as the gear 43 is rotated. Meshing with and driving the gear 43 is a spur gear 51 (see Fig. 5) secured to a vertical shaft 52 likewise journaled in bearings supported within the top cover 29 and the upper housing 47. Journaled on a bearing sleeve 53, supported by the shaft 52, is a bevel gear 54; and a sliding jaw clutch member 55, splined at 56 to the shaft 52, serves to connect the bevel gear 54 to the shaft. A shipper yoke 57 engages the clutch member 55 and is fixed to a shipper rod 58 provided with a handle 59 arranged exteriorly of the upper housing 47. Meshing with and driving the bevel gear 54 is a bevel pinion 60 secured to a longitudinal shaft 61 suitably journaled in bearings supported within the upper housing 47. The shaft 61 is connected by a releasable coupling 62 to an aligned drive shaft 63 suitably journaled within a bearing supported within a bearing bracket 64 secured to the rear end of the machine frame. Secured to the shaft 63 is a clutch member 65 journaled within the machine frame and provided with a conical bore, in engagement with which a clutch cone 66 is held by a spring 67. The clutch cone 66 is clutched at 68 to a shaft 69 driven by the machine motor 13 in a manner described in the above mentioned patent.

In this illustrative embodiment, the paddles or bladelike scoops 20 have curved scoop portions 71, preferably formed with a concave front face 72 and a convex rear side 73, and these scoop portions have hubs 74 keyed at 75 to the horizontal shafts 22. The shafts 22 are arranged with their axes at right angles to the vertical axes of oscillation of the members 24, and these shafts have portions 76 extending within bores 77 in the members 24 and journaled within the bearings 23, 23 supported within the members 24. Arranged on the shafts 22 between the plate hubs and the adjacent bearings are spacing sleeves 78. The inner ends of the shaft portions 76 have bevel gears 79 secured thereto, and these bevel gears are located in the sealed spaces 42 and mesh with bevel teeth or bevel gear segments 80 formed on cylindrical members 81, arranged in bores 82 formed in the sides of the casing. The members 81 are journaled on bearings 83 supported by the vertical shafts 25 above the members 24, as shown in Fig. 4. The members 81 each has a lateral lug 85 movable horizontally in an arcuate recess 86 in the casing and engageable with the ends 87 of the recess to limit turning movement of the member 81 in opposite directions. Each member 24 has spaced vertical bores 88 located at opposite sides of the bevel gear 79 (Fig. 6), and received in these bores are vertically reciprocable locking plungers 89 and 90 formed with right angle horizontal stems or projections 91 guided in vertical slots 92 in the member 24 (see also Fig. 11). Springs 93 in the bores urge the plungers upwardly to maintain the stems 91 in engagement with oppositely inclined cam surfaces 94 and 95 on the bottom of an arcuate ledge 96 (see also Fig. 10) integral with the casing 15. The members 81 have spaced openings 97 and 98 for receiving the upper ends of the locking plungers 89 and 90 in certain positions of the latter. When the members 81 are locked by the plungers 90 to the members 24, the paddles are locked in their upright operative position so that when the members 24 are rotated, the parts all turn together; and when the members 81 are locked by the plungers 89 to the members 24, the paddles are locked in their in-

operative horizontal retracting position; and when both plungers are held released by the cam surfaces from the apertures in the members 81, the members 24 are free to turn relative to the members 81 to cause the bevel gears and racks to swing the paddles about their horizontal axes from one position to the other, i. e., from an upright operative position to a horizontal retracting position, and vice versa. Thus, as the members 24 are oscillated, the bevel gears and gear segments and the plungers and cam surfaces cause the paddles to move horizontally while held rigid against turning about their horizontal axes, and near the ends of their horizontal strokes cause the paddles to swing upwardly or downwardly about their horizontal axes. As shown, the casing 15 may have side openings 99 so that some of the cuttings may be discharged laterally from the casing-chamber 16.

The mode of operation of the improved cuttings removing mechanism is as follows: During operation of the coal cutting machine, while cutting a horizontal kerf in the coal near the floor level, the cuttings created by the cutter chain are moved rearwardly in the chamber 5 in the lower portion of the machine frame and as the cutter chain moves through the rear portion of its orbit, the cuttings are discharged into the chamber 16 of the casing 15 of the cuttings removing mechanism. When the clutch member 55 is connected, the members 24 are oscillated by the machine motor 13 through the shaft 69, clutch 68, cone clutch 66, 65, shaft 63, coupling 62, shaft 61, bevel gears 60, 54, spur gears 51, 43, the crank pin 48 and slot 49, the oscillatory gear segment member 35, gears 31 and 32, and vertical shafts 25. The paddles oscillate in out of step relation so that when one of the paddles is being retracted, the other paddle is moving outwardly to eject the cuttings from the casing-chamber 16, and when a paddle approaches its innermost retracted position in adjacency to the cutter chain orbit, the lug 85 on the member 81 engaging the end wall 87 of the arcuate slot 86 prevents further turning of the member 81; and as the member 24 continues to turn, the bevel gear 79 rolls along the then stationary rack 80 to turn the shaft 22 to swing the paddle from its inoperative horizontal retracting position downwardly about the horizontal axis of the shaft 22 to its upright operative position. The plunger 90 is then permitted to move by the cam surfaces 95 under the influence of its spring 93 into the aperture 98 in the member 81 to lock the members 81 and 24 together; and as the oscillatory gear segment member 35 swings in the opposite direction, the paddle is rigidly maintained upright and swings rearwardly and outwardly about the axis of the member 24 to move the cuttings in the casing-chamber 16 and to eject the cuttings from the casing-chamber. When the paddle approaches its outward discharging position, the lug 85 on the member 81 engaging the end wall 87 of the arcuate recess 86 prevents further turning of the member 81 and the locking plunger is released by the cam surface so that the member 24 may turn relative to the member 81 to cause swinging of the paddle as a result of the relative movement of the bevel pinion 79 and rack 80 from its upright position rearwardly and upwardly to its horizontal inoperative position. The plunger 89 then moves into the aperture 97 so that the parts 24 and 81 are locked together during retracting movement of the paddle.

Referring to movements of the paddle or scoop structure more in detail, it will be noted that in Fig. 6 the left hand paddle A is shown approaching its innermost retracted position, and as it continues to move inwardly, the paddle is swung downwardly about the axis of the horizontal shaft 22 to its upright operative position shown in Fig. 13 and it is locked in such position by one of the locking plungers, connecting the members 81 and 24 together. The paddle A, while maintained in its upright scooping position, is then swung horizontally about the axis of its member 24 to move the cuttings rearwardly in the casing-chamber and to eject the cuttings from the casing-chamber. When the paddle A reaches the position shown in Fig. 14, and it approaches its outermost position, the plunger lock is released by the cam surface and the member 81 is held against further turning so that the paddle is swung through the bevel gear and gear segment about the axis of the shaft 22 rearwardly and upwardly to its horizontal inoperative position shown in Fig. 15. The members 81 and 24 are then locked together by one of the locking plungers, and as the oscillatory gear segment member 35 swings in the opposite direction, the paddle A is swung horizontally inwardly about the axis of the member 24 back to the position shown in Fig. 6. The right hand paddle B has, in Figs. 6, 13, 14 and 15, the same sequence of movements but in out of step relation with the paddle A. In Fig. 6, the paddle B is moving outwardly to move the cuttings rearwardly in the casing-chamber 16 and to eject the cuttings from the casing-chamber; and in Fig. 13, the paddle B has reached the end of its outward travel and has turned upwardly on its horizontal pivot to its inoperative retracting position. In Fig. 14, the paddle B is approaching the end of its inward travel; and in Fig. 15, the paddle B has swung on its horizontal axis downwardly to its upright scooping position and is ready to again move outwardly to move and eject the cuttings. The lugs 85 on the members 81, engaging the ends 87 of the arcuate recesses 86, limit the range of horizontal movement of the paddles while held in either upright operative position during outward movement or in inoperative horizontal position during retracting movement, and during such horizontal movements, the parts 81 and 24 are locked to turn together by the locking plungers. When the lugs 85 engage one end or the other of the arcuate recesses 86, and the cam surfaces have depressed the locking plungers so that the members 24 may turn relative to the members 81, the bevel gears 79 roll along the then stationary racks 80, swinging the paddles about the axes of the horizontal shafts 22 near the end of each horizontal stroke. It is accordingly evident that the paddles swing rearwardly and outwardly to move and eject the cuttings and are then automatically folded into an inoperative horizontal edgewise position so that during their retracting movement, the tendency to move the cuttings rearwardly toward the cutter chain is reduced to a minimum, and just as soon as the paddles approach their innermost retracted position, they are automatically again turned into their upright operative position ready to again move and eject the cuttings.

As a result of this invention, an improved cuttings removing mechanism is provided which may be associated with and driven by a conventional coal cutting machine for effectively removing the cuttings from the vicinity of the cut-

ter chain and for ejecting the cuttings rearwardly out of the machine path. By the provision of the improved oscillatory paddle structure, the cuttings are effectually moved rearwardly and ejected; and when the paddles approach their outermost positions, they are automatically folded into a relatively narrow space so that during retracting strokes of the paddles, the tendency of moving the cuttings rearwardly toward the cutter chain is reduced to a minimum. The improved oscillatory paddle structure is relatively compact and rugged in design, and, due to the novel paddle arrangement disclosed, efficient removal of the cuttings is effected. Other manners of use and advantages of the invention will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. A cuttings removing mechanism comprising a casing having a horizontal chamber for receiving cuttings, and cuttings moving and ejecting means in said casing-chamber for moving the cuttings rearwardly therein and for ejecting the cuttings therefrom, said moving and ejecting means comprising a cuttings moving member which is normally upright when in its cuttings moving and ejecting position, means for pivotally mounting said cuttings moving member on said casing for horizontal oscillatory movement about a vertical axis and for up and down oscillatory movement about a horizontal axis, said member movable into a horizontal inoperative position about said horizontal axis, and motor driven mechanism for effecting actuation of said member during its operation including means connected to said cuttings moving member for oscillating said member about said vertical axis, and means connected to said cuttings moving member for positively turning said member from its upright operative position to its horizontal inoperative position near the end of its horizontal movement in one direction and from its inoperative position to its upright operative position near the end of its travel in the opposite direction.

2. A cuttings removing mechanism comprising a casing having a chamber for receiving cuttings, and cuttings moving and ejecting means in said casing-chamber for moving the cuttings rearwardly therein and for ejecting the cuttings therefrom, said moving and ejecting means comprising a relatively narrow paddle which is normally upright when in its cuttings moving and ejecting position, means for mounting said paddle on said casing to swing horizontally outwardly in said casing-chamber when in said upright position about a vertical axis and to turn into a horizontal inoperative position, and motor operated mechanism for effecting actuation of said paddle during its operation including means connected to said paddle for swinging said paddle about said vertical axis in said horizontal inoperative position to retract said paddle and outwardly when in said upright position, and means connected to said paddle for positively turning said paddle near the end of its outward movement into its horizontal inopera-

tive position wherein it occupies a relatively narrow vertical space and for maintaining said paddle in such position during horizontal retraction of the paddle, said last mentioned means also positively turning the paddle into its upright effective position as it approaches the end of its inward travel in said casing-chamber.

3. A cuttings removing mechanism comprising a casing having a chamber for receiving cuttings, and cuttings moving and ejecting means in said casing-chamber for moving the cuttings rearwardly therein and for ejecting the cuttings therefrom, said moving and ejecting means comprising a member mounted for horizontal oscillatory movement about an upright axis, a horizontal support mounted at its inner end on said member to turn relative thereto about a horizontal axis at right angles to said vertical axis, a paddle secured to the outer end of said turnable support, and motor operated mechanism for effecting actuation of said paddle during its operation including means connected to said member for oscillating the latter, a releasable locking device for securing said horizontal support against turning movement about said horizontal axis relative to said member during a portion of the oscillatory movement of said member and releasable during the remaining portions of such movement, and means effective when said locking device is released for turning said horizontal support about said horizontal axis relative to said member during the remaining portions of said oscillatory movement of said member.

4. A cuttings removing mechanism comprising a casing having a chamber for receiving cuttings, and cuttings moving and ejecting means in said casing-chamber for moving the cuttings rearwardly therein and for ejecting the cuttings therefrom, said cuttings and ejecting means comprising a pair of cooperating paddles which are normally upright and arranged for horizontal swinging in out-of-step relation in said casing-chamber, bearing mountings for supporting said paddles in said casing for such horizontal swinging movement and for turning movement into a horizontal inoperative position, and motor driven mechanism for effecting actuation of said paddles during their operation including means for swinging said paddles inwardly and outwardly in said casing-chamber, locking devices for maintaining said paddles in an upright operative position during outward swinging movement of said paddles in said casing-chamber and automatically releasable as said paddles approach the ends of said horizontal swinging movement in either direction, and means effective as said paddles approach their outward position and when said locking devices are released for turning said paddles from their upright operative position into said horizontal inoperative position wherein they occupy a relatively narrow vertical space and to maintain them in such inoperative position during inward swinging movement of said paddles.

5. A cuttings removing mechanism comprising a casing having a chamber for receiving cuttings, and cuttings moving and ejecting means in said casing-chamber for moving the cuttings rearwardly therein and for ejecting the cuttings therefrom, said cuttings and ejecting means comprising a pair of cooperating paddles which are normally upright and arranged for horizontal swinging movement in out-of-step relation in said casing-chamber, bearing mountings for supporting said paddles in said casing for such horizontal swinging movement and for turning move-

ment into a horizontal inoperative position, and motor driven mechanism for effecting actuation of said paddles during their operation including means for swinging said paddles inwardly and outwardly in said casing-chamber, releasable locking devices for maintaining said paddles in an upright operative position during outward swinging movement of said paddles in said casing-chamber and automatically releasable as said paddles approach the ends of their horizontal swinging movement in either direction, and means effective as said paddles approach their outward position and when said locking devices are released for turning said paddles from their upright position into said horizontal inoperative position wherein they occupy a relatively narrow vertical space and to maintain them in such inoperative position during inward swinging movement of said paddles, said last mentioned means also effective when said paddles approach their innermost position to turn said paddles back into their normal upright operative position.

6. A cuttings removing mechanism comprising a casing having a chamber for receiving cuttings, and cuttings moving and ejecting means in said casing-chamber for moving the cuttings rearwardly therein and for ejecting the cuttings therefrom comprising a cuttings moving and ejecting device when in upright operative cuttings moving position occupying substantially the full height of said casing-chamber and arranged in said casing-chamber to swing horizontally rearwardly therein to move the cuttings outwardly in said casing-chamber and for ejecting the cuttings from said chamber, mounting means on said casing for said cuttings moving and ejecting device for supporting the latter for such horizontal swinging movement and for movement into an inoperative position, and motor driven mechanism for effecting actuation of said cuttings moving and ejecting device including means for swinging said cuttings moving and ejecting device inwardly and outwardly, and means for moving said cuttings moving and ejecting device when the latter approaches its outer ejecting position in said casing-chamber into an inoperative horizontal position wherein it occupies a relatively small portion of the height of said casing-chamber and for maintaining the same in such inoperative position during inward swinging movement of said device in said casing-chamber.

7. A cuttings removing mechanism comprising a casing having a chamber for receiving cuttings, and cuttings moving and ejecting means in said casing-chamber for moving the cuttings rearwardly therein and for ejecting the cuttings therefrom comprising a cuttings moving and ejecting device when in upright operative cuttings moving position occupying substantially the full height of said casing-chamber and arranged in said casing-chamber to swing horizontally outwardly therein to move the cuttings rearwardly in said casing-chamber to eject the cuttings from said chamber and to swing horizontally inwardly toward retracted position, mounting means on said casing for said cuttings moving and ejecting device for supporting the latter for such horizontal swinging movement and for movement into an inoperative position, and motor driven mechanism for effecting actuation of said cuttings moving and ejecting device including means for swinging said cuttings moving and ejecting device inwardly and outwardly, and means for moving said cuttings moving and ejecting device when the latter approaches its outer ejecting

position in said casing-chamber into an inoperative horizontal position wherein it occupies a relatively small portion of the height of said casing-chamber and for maintaining said device in such inoperative position during retraction thereof in said casing-chamber, said last mentioned means also effective when said cuttings moving and ejecting device approaches its inward retracted position to return the same to its operative upright cuttings moving position.

8. A cuttings removing mechanism comprising a casing having a cuttings receiving chamber, and cuttings moving and ejecting means comprising an upright bladelike scoop when in operative cuttings moving position occupying substantially the full height of said chamber, means for mounting said scoop on said casing for horizontal swinging movement in said casing-chamber and for movement into a horizontal inoperative position, and motor driven mechanism for effecting actuation of said scoop during its operation including means for swinging said scoop horizontally outwardly in said chamber to move the cuttings rearwardly in said chamber to eject the cuttings from said chamber and for swinging said scoop horizontally inwardly to retract the latter, and means for moving said scoop into an inoperative horizontal position wherein it occupies a relatively small portion of the height of said chamber as said scoop approaches the end of its outward travel in said chamber and for maintaining the scoop in such position during swinging retraction thereof.

9. A cuttings removing mechanism comprising a casing having a cuttings receiving chamber, and cuttings moving and ejecting means comprising a normally upright bladelike scoop, bearing means for mounting said scoop on said casing for horizontal swinging movement in said casing-chamber and for turning movement into a horizontal inoperative position, and motor driven mechanism for effecting actuation of said upright scoop during its operation including means for swinging said scoop horizontally outwardly to move the cuttings rearwardly in said chamber to eject the cuttings from said chamber and for swinging said scoop horizontally inwardly to retract the latter, and means for turning said scoop from its upright operative position into its inoperative horizontal position as said scoop approaches the end of its outward travel in said chamber and for maintaining the scoop in such horizontal position during swinging retraction thereof, said last mentioned means also turning said scoop back to its upright operative position when said scoop approaches the end of its inward swinging retractive movement.

10. A cuttings removing mechanism comprising a casing having a cuttings receiving chamber, and cuttings moving and ejecting means including a normally upright cuttings moving and ejecting member arranged in said casing-chamber to swing horizontally in and out thereby to move the cuttings rearwardly in said chamber and for ejecting the cuttings rearwardly from said chamber, bearing means for mounting said member at one end thereof on said casing for horizontal swinging movement and for turning movement into a horizontal folded position, and motor driven mechanism for effecting actuation of said cuttings moving and ejecting member including means for swinging said member inwardly and outwardly, means operatively connected to said end of said member for turning said member as the latter approaches the end of

its outward movement into its folded inoperative horizontal position and for maintaining it in such horizontal position during inward swinging movement of said member in said chamber.

5 11. A cuttings removing mechanism comprising a casing having a cuttings receiving chamber, and cuttings moving and ejecting means including a cuttings moving and ejecting member arranged in said casing-chamber to swing horizontally outwardly when in upright position thereby to move the cuttings rearwardly in said chamber and for ejecting the cuttings rearwardly from said chamber, means for mounting said member at one end thereof on said casing for horizontal swinging movement and for movement into an inoperative horizontal position, and mechanism for effecting actuation of said cuttings moving and ejecting member including means for moving said upright member inwardly and outwardly, and means operatively connected to said end of said member for moving said member as said member approaches the end of its outward swinging movement into its horizontal inoperative position and for maintaining it in such position during inward swinging movement of said member, said last mentioned means also for returning said member to its operative position as said member approaches the end of its inward swinging movement.

30 12. A cuttings removing mechanism comprising a casing having a chamber for receiving cuttings, and cuttings moving and ejecting means in said casing-chamber for moving the cuttings outwardly therein and for ejecting the cuttings therefrom, said cuttings moving and ejecting means comprising a pair of cooperating relatively movable paddles adapted to assume upright operative positions and arranged for horizontal swinging movement in said casing-member, bearing mountings at the sides of said casing for pivotally mounting said paddles at one end to swing horizontally outwardly and inwardly in said chamber, said paddles projecting freely horizontally partly across said casing-chamber with their free ends in adjacency to the longitudinal center of said casing, said paddles when in their upright operative cuttings moving and ejecting position extending substantially the full height of said casing-chamber, motor driven means for swinging said paddles outwardly about their pivots when in their upright operative cuttings moving and ejecting position, mounting means for pivotally mounting said paddles to turn about horizontal axes whereby said paddles may turn into an inoperative horizontal position wherein they occupy only a relatively small portion of the height of said casing-chamber during inward swinging movement of said paddles, thereby to reduce the moving back of cuttings in said chamber, and means effective during horizontal swinging of said paddles for turning said paddles about said horizontal axes into either said upright operative position or said inoperative horizontal position.

65 13. A cuttings removing mechanism comprising a casing having a cuttings receiving chamber, and cuttings moving and ejecting means carried by said casing comprising an oscillatory paddle which when in operative cuttings moving and ejecting position is substantially upright and occupies substantially the full height of said chamber, a bearing mounting for supporting said paddle for horizontal swinging movement in said chamber about a vertical axis and for turning movement between its upright operative posi-

tion and a horizontal inoperative position about a horizontal axis, motor driven gearing for swinging said paddle horizontally on its bearing mounting, a cam operated locking device for automatically releasing said paddle from said driving gearing when said paddle is swung horizontally a predetermined distance in either direction, said cam operated locking device locking said paddle against turning movement about said horizontal axis during horizontal swinging of said paddle and including cam means for releasing said locking device as said paddle approaches the end of its horizontal swinging movement in either direction, and gearing driven by said first mentioned gearing and effective when said locking device is released for turning said paddle about said horizontal axis into either its upright operative position or its horizontal inoperative position.

14. A cuttings removing mechanism as set forth in claim 13 wherein said motor driven gearing and bearing mounting include coaxial members, one carrying said paddle and with which said paddle is swingable horizontally and on which said paddle is mounted to turn on a horizontal axis and constituting a driven member driven by said motor driven gearing and said other member adapted to rotate with said driven member or remain relatively stationary, and said locking devices acting to lock said coaxial members together to effect horizontal swinging movement of said paddle and automatically releasable near the ends of the horizontal swinging movement of said paddle in either direction,

and said coaxial members having relative rotation when said locking devices are released, and said second mentioned gearing being operatively associated with said other member and having an element driven by said driven member and effecting relative rotation of said coaxial members to turn said paddle about said horizontal axis when said locking devices are released.

15. A cuttings removing mechanism as set forth in claim 14 wherein said motor driven gearing includes an oscillatory gear segment swingable about a vertical axis and a gear meshing with said gear segment and connected to said driven member for intermittently rotating the latter in opposite directions as said gear segment is oscillated, and a motor driven crank for oscillating said gear segment.

JOHN A. HAYWARD.
